GRINDING MILL

Kristian Middelboe, Frederiksberg, near Copenhagen, Denmark, assignor to F. L. Smith & Co., New York, N. Y., a corporation of New Jersey

Application June 25, 1931, Serial No. 546,733,
and in Great Britain February 9, 1931

2 Claims. (Cl. 83—45)

This invention relates to the fine grinding of coal, pigments, raw materials for the manufacture of cement, cement clinker, and the like, in high-speed mills in which the material is ground by rolling and crushing between rotating grinding surfaces, the grinding bodies, such as large balls, cylinders, or other solids of revolution being pressed by centrifugal or other force against the inner surface of an enclosing grinding ring, which may be either rotary or stationary, while the grinding bodies are caused to revolve.

In the operation of mills of this kind the contact surfaces of the grinding bodies and of the grinding ring, wear unevenly and lose true sphericity or cylindricity because the hardness and wear resistance of the contact surfaces are never quite uniform at all points. This leads to the development of shocks and vibrations, the effect of which is multiplied by reason of the load of the grinding bodies, and consequently necessitates frequent replacements of the machine parts.

This difficulty is overcome by the present invention in accordance with which the grinding bodies are coupled together in multiples by a rigid connection, whereby the tendency of each separate grinding body to deepen and increase incipient unevenness of the grinding surfaces is overcome. The invention may be embodied in various forms of the intercoupling of the grinding bodies, by which a smooth running of the mill is ensured. The distances between the grinding bodies are preferably made different, and when the grinding bodies are coupled together in pairs only, the rigid connection between the two grinding bodies of a pair is effected in such a manner that neither of the said bodies can move at right angles to a plane which passes through their points of contact with the grinding ring and is parallel to a plane through their axes of rotation. As a result of these arrangements, irregularities in the grinding surfaces are not exposed to the heavy shocks which would be exerted by a single freely movable grinding body.

The coupling of the grinding bodies together in the manner described reduces the pressure of each upon incipient depressions in the grinding surfaces, while the pressure is increased correspondingly on hard and projecting points. The grinding bodies may contact with the inner, concave grinding surface of an enclosing grinding ring as heretofore, but the invention contemplates also a relative arrangement of grinding ring and grinding bodies such that the grinding bodies work against the outer, con-

vex surface of the grinding ring rather than the inner concave surface.

In the grinding of moist and sticky material the tendency of the grinding surface of the grinding ring to be coated with such material, with a resultant reduced grinding efficiency, is diminished.

The invention will now be described with reference to the accompanying drawings, wherein:

Figures 1 and 2 are views in vertical and horizontal section of a grinding mill which embodies the present invention, and

Figure 3 is a view in horizontal section of a modified form of construction.

As will be seen in Figures 1 and 2, the mill is provided with a casing 1 within which the grinding is effected by a rolling or crushing action between rotating grinding surfaces. In this particular case, these grinding surfaces are formed by a grinding ring 2 which rotates about the vertical axis of the mill and provides an outer convex grinding surface, and by six cylindrical grinding bodies 3. The grinding ring is supported by a shaft 4 driven through gearing 5. The grinding bodies 3 are secured to vertical shafts 6, each of which is suspended in a collar-thrust-bearing 7 and is guided below by a bearing 8. Both of these bearings are carried by a common housing 9. The housings are rigidly connected together in pairs, that is, at fixed distances apart and without freedom for relative movement about a vertical axis by frames 9^a and at the upper end are suspended so as to swing on a horizontal axis by pivots 10 in bearings outside the casing. By this method of suspension and coupling together of the grinding bodies in pairs, the individual grinding bodies are prevented from moving independently of each other at right angles to a plane which passes through their points of contact with the grinding ring and is parallel to their axes of rotation. The grinding bodies of each set are together pressed against the grinding ring by means of springs 11 which may be connected at their ends to lugs 9^b of adjacent frames 9^a.

A smooth running of the mill may be further ensured by making unequal the distances between the grinding bodies of different pairs so that the coupled grinding bodies do not readily form corresponding depressions in the grinding surface of the ring 2.

The material to be ground is supplied to the mill through chutes 12 arranged in a circle, by which the material is led down directly in front of each grinding body 3, in such a manner that the material is immediately caught and crushed

between the rotating grinding surfaces. The lower portions 13 of the chutes 12 are related telescopically to the chutes 12, and are suspended in a frame 14, which can be moved upwards and downwards by suitable means indicated at 5 15, whereby the material to be ground may be distributed over the entire height of the grinding surfaces. When the material has passed between the grinding ring and the grinding bodies, 10 it is caught at the bottom of the casing by blades 16 secured to the shaft 4, by which it is projected outwardly through a discharge pipe 17. At this stage, fines of the material being ground may be separated and carried off while the coarser particles 15 may be returned to the mill.

Figure 3, in which similar reference characters indicate corresponding parts, shows a rigid inter-coupling of the grinding bodies in threes. The above described pivotal suspension of the 20 supporting frames is not so necessary in this case for preventing the individual grinding bodies from increasing incipient unevenness in the grinding surfaces, as two of the grinding bodies will prevent the third from moving freely and independently against the grinding ring.

It will be noted that each supporting frame composed of the housings 9 and the connecting frame 9^a and the bearings, is rigid in itself and is movable as a unit toward the grinding ring under the influence of the springs 11, without movement of oscillation about a vertical axis, that the grinding bodies of each set are supported on fixed axes in the frame at fixed distances apart, although the distance between the grinding bodies 30 35 of each set may be different from the distance between the grinding bodies of every other set, and that each frame and the grinding bodies sup-

ported by it are pressed toward the grinding ring as a unit independently of each other frame. In this manner when one of the rollers of a set bears against the grinding ring the other roller or rollers of that set are prevented from entering any incipient recess in the grinding ring. 80

It will be seen that the coupled grinding bodies might be arranged to bear against the inner, concave surface of an encompassing grinding ring and that other changes might be made to suit 85 different conditions of use, the invention not being restricted to any particular construction, except as pointed out in the accompanying claims.

I claim as my invention:

1. In a grinding mill, the combination of a 90 grinding ring, a plurality of rigid supporting frames, each frame being movable as a unit toward and from the grinding ring without movement about a vertical axis, a plurality of grinding bodies supported on fixed axes in each frame 95 at a fixed distance apart, and means to press each frame and the grinding bodies supported by it as a unit together toward the grinding ring.

2. In a grinding mill, the combination of a 100 grinding ring, a plurality of rigid supporting frames, each frame being movable as a unit toward and from the grinding ring without movement about a vertical axis, a plurality of grinding bodies supported on fixed axes in each frame 105 at a fixed distance apart, and means to press each frame and the grinding bodies supported by it as a unit together toward the grinding ring, each frame being pivotally supported so as to swing on a horizontal axis toward the grinding ring. 110
